UNITED STATES PATENT OFFICE.

BENJAMIN R. GILMOUR, OF YONKERS, NEW YORK.

GAME.

Application filed April 12, 1924. Serial No. 706,182.

This invention relates to games and more particularly to a game for children in the nature of a contest which is both entertaining and instructive.

5 The principal object of the invention is to provide a game which is attractive to children, holds their interest, and at the same time provides mental and moral training for them without their being conscious that this

10 is so.

In the preferred form of the invention, and as herein illustrated, provision may be made of a game board having a path or course divided into spaces forming units of progress, which path leads from a common starting point for the contestants to a common goal. Pieces may be used to represent or designate the players and a spinner may be provided for variably controlling the 20 number of units that a player may advance his piece at a turn.

In accordance with one feature of the invention the spaces of the path bear suitable pictorial illustrations or printing which 25 designate the various incidents relating to the child's cleanliness and health and to his food, which if followed through the course of each day will lead him to a healthy life, in a manner analogous to the way he is lead 30 to the goal of "health" on the game board.

According to a further very important feature of the invention certain of the designations are indicative of misconduct of faults and to these appropriate penalties are attached. The actual penalty imposed is in 35 the nature of a setback of the player's piece, but this is expressed on the board, for example, in regard to points of health and cleanliness, as "Forgot to wash. Go back 40 to soap." Or in regard to healthful food as "Coffee. Go back to cocoa." It will, of course, be the earnest desire of the players to avoid these penalty spaces; hence, these 45 spaces will be noticed more than the others, and the faults to which the penalties are attached will be impressed on the minds of the children in association with a desire to avoid or correct them both in playing the game and in the incidents of their daily life.

50 It is an object of the invention to teach concentration and encourage memorization. To this end the course of progress is made labyrinthical and includes no indication of the direction of movement toward the goal, and the spaces are sufficiently numerous to make it difficult to determine this direction

by inspection. The player, therefore, is required to bear in mind the direction from which his piece was advanced to a given point, since otherwise he is apt to move it 60 backward toward the starting point instead of toward the goal. This liability gives rise to much amusement on the part of the players and at the same time trains them to concentrate. 65

The danger of moving backward by mistake furnishes an incentive to memorize the arrangement of the board, and to enable this to be done without too great difficulty illustrations which may be of certain nationally 70 known food and toilet articles are provided at selected spaces. These illustrations serve as landmarks with reference to which the direction of movement can be remembered and they also serve to impress upon the children 75 the names of standard food and toilet articles.

Other features and advantages will hereinafter appear.

In the accompanying drawing forming a 80 part of this specification:

Figure 1 is a plan view of the game board.

Figure 2 shows a spinner for determining the number of units a contestant is entitled to advance his piece at a turn; and 85

Figure 3 is a view of several of the pieces which may be used on the board to represent the contestants.

A game board 1 is subdivided into squares 2, having openings 3 in their sides to indicate the path to be followed in passing from square to square. A spinner 4 comprising a numeral bearing dial 5 and a rotatable indicator hand 6, is provided to be spun in turn by the players. Pieces 7 suitably distinguished from each other by color or otherwise may be used to represent the players on the board, each player being entitled to advance his piece the number of spaces indicated by his turn of the spinner hand 6. 95

As shown herein the players start from a space marked "Early rise" at the lower right hand corner of the board and thence progress by a tortuous course through the various squares of the board representing incidents in the daily life of the child to the goal 8 at the center marked "Health". Some of the spaces along the route are marked to indicate the occurrence of various incidents familiar to children, certain of them being 105 designed to be amusing, others instructive and others merely to carry out the analogy 110

to the experiences of a child's day, all to carry home to the child the course he should follow to gain the goal of health in life.

Some of the spaces designate duties to be performed while others are penalty spaces, indicating a dereliction of duty and requiring that the player set his piece back to the duty space. Of the penalty class are such spaces as "Tea. Go back to milk" "Window closed. Go back to fresh air". This idea may also be extended to include the provision of rewards for exceptional good conduct.

The individual incident designations on the board are self-explanatory as illustrated in the drawing and will not therefore be explained in detail here. They are arranged generally from the point of beginning to the goal in the same sequence in which they would be likely to occur in the course of a day.

Where certain of the items are to be used together to attain the goal of health as for example, "Bath tub" and "Soap" or "Bread" and "Butter" the instructions of the game may be such that if the spin of the dial puts the player in the square "Bath tub" he cannot skip the square "Soap" but must continue to spin the dial in his regular turn until he strikes the number which will put him in the square "Soap" etc.

The course indicated to be followed by the openings between the spaces is in the nature of a maze or labyrinth, the spaces being numerous and the path being tortuous. It is accordingly difficult for a contestant to determine whether he is moving his piece toward the goal or in the reverse direction, and no ready clue to this is provided. There is accordingly a likelihood that a contestant will move his piece away from the goal instead of toward it, and this possibility of error gives rise to much amusement, and encourages the child to concentrate his mind upon the way by which a square has been reached in order that he may avoid retracing his course.

The fact that the correct direction of movement of a piece is hard to determine by inspection furnishes an incentive to memorize the arrangement of the board, and such memorization may be encouraged and aided by providing illustrations of the incidents referred to in selected squares. These illustrated squares serve as points of reference, because of the vivid impression which they make upon the eye, in a much more effective manner than mere printed words could do, and at the same time add interest to the incidents illustrated by them, add life to the appearance of the board and serve as an effective advertising medium for any particular brand of food or toilet product illustrated thereon. They also attract the attention of prospective purchasers to the char-

acter of the game when it is on display for sale, and afford an easy means of identifying it.

It will be seen that a game of this character is of value not only for its direct effect in entertaining and instructing the children, but that it is helpful to the mother as well because it relieves her of their care while the game is in progress and because it eliminates the need for much nagging criticism by her to impress upon the child the various rules as to cleanliness and eating which it should observe which is wearing on her nerves and is distasteful to the children.

A wide range of variations and modifications may be resorted to within the scope of the invention and part of the features may be used without others.

I claim:

1. In a game for children, a plurality of pieces, means for controlling the advance of said pieces and a game board including a point of beginning, a goal and a path connecting the point of beginning and the goal, divided into spaces, a fixed point of entrance and exit in each space, said points of entrance and exit being variously located in the spaces forming a path sufficiently tortuous and comprising a sufficient number of spaces to form an uncharted maze or labyrinth, the arrangement being such that a player cannot readily determine by inspection of the board the direction in which his piece should be moved in order to progress toward the goal, so that a child playing the game is required to fix in his mind the way by which a given point was reached in order to avoid retracing his course.

2. A game for children comprising a plurality of pieces, means for determining the advance of the pieces, and a game board including a point of beginning, a goal toward which the pieces advance from the point of beginning, a path connecting the point of beginning and the goal, comprising a plurality of spaces having fixed points for entrance and exit differently arranged and without indications as to the direction of progress, said spaces consisting of progress spaces and penalty spaces, said spaces having designations indicative of the common experiences of children, said designations being arranged from the point of beginning to the goal in the order of their probable occurrence throughout a day, whereby the progress of a player's piece from the point of beginning to the goal is caused to bear analogy to the experiences of a day in the order of their occurrence.

3. A game for children comprising a plurality of pieces, means for determining the advance of the pieces, and a game board including a point of beginning, a goal toward which the pieces advance from the point of beginning, a path connecting the point of

beginning and the goal, comprising a plurality of spaces having fixed points for entrance and exit differently arranged and without indications as to the direction of progress, said spaces consisting of progress spaces and penalty spaces, said spaces having designations which by analogy refer to incidents of the child's daily life relating to health, food and cleanliness, pictorial designations of food and toilet articles in some of said spaces, said designations being ar-

ranged from the point of beginning to the goal in the order of their probable occurrence throughout a day, whereby the progress of a player's piece from the point of beginning to the goal is caused to bear analogy to the experiences of a day in the order of their occurrence.

In testimony whereof I have affixed my signature.

BENJAMIN R. GILMOUR.
